UNITED STATES PATENT OFFICE.

VINCENZO F. MELFI, OF NEW YORK, N. Y.

DETACHABLE BUTTON.

1,368,277.

Specification of Letters Patent.

Patented Feb. 15, 1921.

Application filed June 12, 1920. Serial No. 388,683.

To all whom it may concern:

Be it known that I, VINCENZO F. MELFI, a citizen of the United States, residing at the borough of Manhattan, in the city, county, and State of New York, have invented certain new and useful Improvements in Detachable Buttons, of which the following is a specification, reference being had therein to the accompanying drawings, 10 which form a part thereof.

My invention relates to detachable buttons, and more particularly to a class of buttons having a solid head composed of bone, rubber or other similar gums, or a plastic 15 composition, such as are ordinarily used in exposed sections upon outer garments.

Heretofore sheet metal detachable buttons have been extensively made and used, but the construction of such buttons has 20 been such as to adapt them for use as suspender buttons, or in other concealed positions about the garment, and ordinarily no means have been provided to permit the re-setting of the buttons.

25 A button made in accordance with my invention is so constructed that it may be quickly attached to a garment without the use of a needle and thread, and without cutting the threads of the fabric, while being 30 capable of being as quickly detached from the garment and reset, as in the case of a re-fitting of the garment, without such mutilation of the fabric as will require mending, or be unsightly.

35 When applied to a garment it will not be noticeably different from an ordinary button used in the same position, will not accumulate dust and dirt and will have a leg of sufficient length to afford proper space 40 and flexibility in and about the button to permit the head to be quickly and properly passed through a co-operating buttonhole and avoid wrinkling of the fabric about the button.

45 Buttons embodying my invention may be produced at a cost but little in excess of that of the ordinary bone, rubber or composition button and may be attractively packed, fully assembled, either upon cards or in boxes.

50 In use the metallic parts of the button are so protected and concealed as not to be subject to deterioration, nor to become unsightly after prolonged use.

55 While the button may be quickly detached from a garment, its construction

is such that accidental detachment thereof is prevented.

The invention consists primarily in a detachable button embodying therein a solid head having an opening therethrough, the 60 wall of said opening being recessed, and attaching means comprising a back plate having an opening therethrough, a plurality of yieldable tongues projecting therefrom about said opening, an overhang on, 65 and extending outwardly of, each of said tongues, said tongues being adapted to enter the opening in said head and the overhang thereof being adopted to enter the recessed portion thereof, and a removable wedge 70 adapted to pass through the opening in said head, between said tongues and into the opening in said plate, whereby the overhang of said tongues will be forced into said recessed portion and said tongues will be held 75 against displacement; and in such other novel features of construction and combination of parts as are hereinafter set forth and described, and more particularly pointed out in the claims hereto appended. 80

Referring to the drawings,—

Figure 1 is a plan view, partly in section, of the head of a button embodying one form of my invention;

Fig. 2 is a vertical section of a button 85 as shown in Fig. 1, with the prongs within the opening in the head and the wedge in position to be forced between said tongues, the fully assembled relation of parts being shown in dotted lines; 90

Fig. 3 is a view like Fig. 1, of another form of the invention;

Fig. 4 is a vertical view, like Fig. 2, of the form of invention shown in Fig. 3; and 95

Fig. 5 is a view of the bodkinlike special tool used in attaching and detaching the button.

Like letters refer to like parts throughout the several views.

The several views of the drawings show buttons made in accordance with my invention upon a much enlarged scale, the essential characteristics of my invention being especially applicable to buttons used on suit 105 coats and vests and overcoats.

In both forms of the invention shown, I employ a solid button head *a* composed of bone, vulcanized rubber or other similar gum, or plastic composition, having a cen- 110

tral cylindrical opening a' extending therethrough.

Coöperating with said head is attaching means comprising a back plate b which may be formed of the same materials as the head or of sheet metal, as desired. The plate b has an opening b' therethrough axially aligned with the opening a' in the head a .

Carried by the plate b about the opening b' are a plurality of yieldable tongues c adapted to pass into the opening a' , each of said tongues having an outwardly extending overhang c' at the end thereof adapted, with the separation of the tongues 15 by means of a wedge d , to enter a coöperating recess a^2 in the wall of the opening a' .

About the tongues c , I employ a ring e of soft rubber, cork, felt, or other material, of a thickness to form the leg necessary to be formed in attaching any button to a garment composed of heavy fabric. This ring or washer will also protect and conceal the portions of the tongues between the garment and the head a .

25 A fragmentary portion of the garment is indicated at f in the drawings.

The opening a' is utilized solely for receiving and retaining the lugs c and applying the wedge d thereto in assembling the 30 button, while the opening b' is utilized to permit access to said wedge to facilitate its removal to permit the separation of the head from the attaching means.

The structural characteristics above described are common to both forms of the invention shown, the sole difference of structure between the form shown in Figs. 1 and 2 and the form shown in Figs. 3 and 40 4 being in the incorporation in the former of characteristics preventing rotation of the head upon the tongues c , which are absent in the latter.

45 Referring more particularly to Figs. 1 and 2 of the drawings, I provide the opening a' with a plurality of slots a^3 extending longitudinally in the wall thereof, each of said slots being adapted to receive a tongue c so as to prevent relative rotary movement of the head a and its coöperating attaching means. In this form of the invention, the 50 recessed portion a^2 of the opening a' opens into the top face of the head a , and leads from the tops of the respective longitudinal slots or channels a^3 .

55 In this form of the invention, I employ a double truncated conical wedge d , the lower trunk d' of which serves to impart an initial outward flexure of the tongues c to engage the overhang c' of each 60 tongue with its recess a^2 , and thereafter force the several tongues within the respective slots or channels a^3 . The upper trunk d^2 merely serves to force the tops of the several tongues c outwardly to facilitate the 65 entrance of the cylindrical head of the

wedge d and permit the top thereof to come flush with the upper face of the head a .

Referring more particularly to Figs. 3 and 4 of the drawings, the recess a^2 is in the form of a peripheral groove or channel 70 in the wall of the opening a' about midway of the length of said opening. The wedge d is a single truncated conical wedge, the trunk d^3 of which serves merely to force the overhang c' of each tongue c into said 75 groove or channel a^2 and prevent its escape therefrom. The head of the wedge is cylindrical and there is a narrow shoulder d^4 about same presented toward the trunk d^3 adapted to engage the tops of the several 80 tongues, and thus position the top of the wedge substantially flush with the upper face of the head a .

As stated above, the peripheral groove or channel forming the recess a^2 permits rotation of the head with relation to the tongue c , and while this does not affect the operativeness of the button, it may be desired in some instances to avoid this condition.

90 The wedge d , in each form of the invention shown, is provided with a reduced cylindrical end g adapted to enter the opening b' with the lower face thereof slightly above the lower face of the plate b .

95 In attaching and detaching a button made in accordance with my invention, I employ a bodkinlike special tool having a reduced stem h adapted to pass through the opening b' and engage the end of a wedge d , 100 and an enlarged conical head h' having a needle-like point, and a recess h^2 about the stem h adapted to receive the overhangs c' of the tongues c of an attaching means. I have found in actual practice that such a 105 tool may be used to pass the tongues through two plies of heavy cloth with the usual interlining, without cutting the weft of the fabric to an extent which will make it possible to detect, after the detachment of the 110 button from the cloth, where a button embodying my invention has been positioned.

115 In attaching a button made in accordance with my invention, the stem h of the bodkin-like tool is passed through the space within the several tongues c and through the opening b' in the plate b . Said tongues are pressed together until the free ends thereof enter the recess h^2 in the head h' . The head h' is then passed through the fabric, the conical head spreading the weft and warp in a manner to provide space for the passage of the tongues c without cutting the 120 yarn.

125 The tool is then withdrawn from the plate b and tongues c and a ring or washer e is passed over the tongues c , or if desired said washer may be passed over the head h' before same is withdrawn, as described.

A button head *a* is then mounted upon the tongues *c*, which enter the opening *a'*, the ring or washer limiting the movement of the head to approximately that required to bring the overhang *c'* of each tongue into the proper position with relation to the recess adapted to receive same.

With the form of invention shown in Figs. 1 and 2, care must be exercised to bring the overhang *c'* of each tongue *c* into a longitudinal channel *a*, a precaution unnecessary with the form of invention shown in Figs. 3 and 4.

When the overhang *c'* of each tongue *c* has been properly positioned to enter its recess *a*, the wedge *d* is passed through the top of the opening *a'* into the space within said tongues, thus forcing the overhang *c'* of the tongues into, and holding them in, the recess *a*. When properly positioned, the top of the wedge *d* will be flush with the upper face of the head *a* and the reduced cylindrical end *g* will be seated in the opening *b'* of the back plate *b* and exposed through the bottom of said opening.

In the form of the invention the trunk *d'* will engage the tongues *c* adjacent the overhangs *c'* and force said overhangs into the recess therefor, during the initial movement of the wedge, and will thereafter hold the tongues *c* in their respective grooves or channels *a*, the trunk *d'* serving to insure forcing the tops of the tongues outwardly to permit the entrance of the cylindrical top of the wedge therebetween and permit it to come flush with the top surface of the head *a*.

In the form of the invention shown in Figs. 3 and 4 there will be a continuing wedging action by the trunk *d* until the shoulder *d'* engages the top of the tongue, at which time the top of the wedge will be flush with the upper surface of the head *a*.

If it be desired to detach a button, the stem *h* is used to force the wedge *d* outwardly of the head *a* by engaging the end of said stem with the end *g*, through the opening *b'*. With the removal of the wedge the tongues *c* will either spring away from the wall of the opening *a'* through elasticity inherent thereto, so as to cause the overhangs to pass from the recess *a*, or will flex under pressure applied thereto through said overhangs and the lower shoulder of the recess, as a result of a pull exerted upon the head *a* with the same result.

When the head *a* has been separated from the attaching means therefor, the tongues *c* may be drawn through the fabric, and the same button may be reapplied to a garment, a condition particularly desirable in fitting and refitting garments.

In use, a button made in accordance with my invention differs in appearance from the ordinary button merely in the absence of the

thread holes, although in the form of the invention shown in Figs. 1 and 2, the exposed ends of the tongues will somewhat resemble such openings.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A detachable button embodying therein a solid head having an opening therethrough, the wall of said opening being recessed, and attaching means comprising a back plate having an opening therethrough, a plurality of yieldable tongues projecting therefrom about said opening, an overhang on, and extending outwardly of, each of said tongues, said tongues being adapted to enter the opening in said head and the overhang thereof being adapted to enter the recessed portion thereof, and a removable wedge adapted to pass through the opening in said head, between said tongues and into the opening in said plate, whereby the overhang of said tongues will be forced into said recessed portion and said tongues will be held against displacement.

2. A detachable button embodying therein a solid head having an opening therethrough, the wall of said opening being recessed, and attaching means comprising a back plate having an opening therethrough, a plurality of yieldable tongues projecting therefrom about said opening, an overhang on, and extending outwardly of, each of said tongues, said tongues being adapted to enter the opening in said head and the overhang thereof being adapted to enter the recessed portion thereof, and a removable wedge adapted to pass through the opening in said head, having a truncated conical portion adapted to enter between said tongues, a cylindrical portion, the top of which is adapted to be brought substantially flush with the upper surface of said head, and a reduced cylindrical portion adapted to enter the opening of said plate and be exposed through the bottom of said opening, whereby the overhangs of said tongues will be forced into said recessed portion and said tongues will be held against displacement.

3. A detachable button embodying therein a solid head having an opening therethrough, the wall of said opening being recessed, and attaching means comprising a back plate having an opening therethrough, a plurality of yieldable tongues projecting therefrom about said opening, an overhang on, and extending outwardly of, each of said tongues, said tongues being adapted to enter the opening in said head and the overhang thereof being adapted to enter the recessed

portion thereof, a resilient ring or washer upon said tongues adjacent said head, and a removable wedge adapted to pass through the opening in said head, between said 5 tongues and into the opening in said plate, whereby the overhang of said tongues will be forced into said recessed portion and said tongues will be held against displacement.

4. A detachable button embodying therein 10 a solid head having an opening therethrough, the wall of said opening being recessed, and attaching means comprising a back plate having an opening therethrough, a plurality of yieldable tongues projecting therefrom about said opening, an overhang on, and extending outwardly of, each of said tongues, said tongues being adapted to enter the opening in said head and the overhang thereof being adapted to enter the recessed 20 portion thereof, means preventing relative rotary movement of said head and said tongues, and a removable wedge adapted to pass through the opening in said head, between said tongues and into the opening in 25 said plate, whereby the overhang of said tongues will be forced into said recessed portion and said tongues will be held against displacement.

5. A detachable button embodying therein 30 a solid head having an opening therethrough, said opening having a plurality of longitudinally extending slots or grooves in the wall thereof, and being recessed adjacent the upper end of each of said slots or grooves, 35 and attaching means comprising a back plate having an opening therethrough, a plurality of yieldable tongues projecting therefrom about said opening, an overhang on, and extending outwardly of, each of said tongues, 40 said tongues being adapted to enter the longitudinal slots or grooves in the wall of the opening of said head, and the overhang thereof being adapted to enter the recessed portion of said opening, and a removable 45 wedge adapted to pass through the opening in said head, between said tongues and into the opening in said plate, whereby said

tongues will be forced into said slots or grooves respectively, and the overhang of each of said tongues will be forced into said recessed portion adjacent said slot or groove, and said tongues will be held against displacement.

6. A detachable button embodying therein 55 a solid head having an opening therethrough, said opening having a plurality of longitudinally extending slots or grooves in the wall thereof, and being recessed adjacent the upper end of each of said slots or grooves, and attaching means comprising a back 60 plate having an opening therethrough, a plurality of yieldable tongues projecting therefrom about said opening, an overhang on, and extending outwardly of, each of said tongues, said tongues being adapted to enter the longitudinal slots or grooves in the wall of the opening of said head, and the overhang thereof being adapted to enter the recessed portion of said opening, and a removable 65 wedge adapted to pass through the opening in said head, said wedge having a cylindrical portion, the top of which is adapted to be brought substantially flush with the upper surface of said head, a truncated conical portion adjacent said last 75 named portion, a reduced cylindrical end adapted to enter the opening in said plate and be exposed through the bottom of said opening, and a truncated conical portion intermediate said reduced cylindrical portion and said first named conical portion, whereby said tongues will be forced into said longitudinal slots or grooves, and said overhangs of said tongues respectively will be forced into said recessed portion, and said 80 tongues will be held against displacement.

In witness whereof I have hereunto affixed my signature, in the presence of two subscribing witnesses, this 9th day of June, 1920.

VINCENZO F. MELFI.
